UNITED STATES PATENT OFFICE.

WILLIAM LESLIE FRENCH, OF NEW YORK, N. Y.

DESIGN FOR A BADGE.

SPECIFICATION forming part of Design No. 28,779, dated June 7, 1898.

Application filed November 19, 1897. Serial No. 659,203. Term of patent 14 years.

To all whom it may concern:

Be it known that I, WILLIAM LESLIE FRENCH, of New York, county of New York, and State of New York, have invented and produced a certain new and useful Design for an Ornament or Badge, of which the following is a specification, reference being had to the accompanying drawing, which forms a part thereof.

- 10 As shown in the drawing, the leading feature of my design consists of a shield provided with a border upon which are ornamental representations of fleur-de-lis. The surface of the shield is divided into four quarters by a vertical cross. Upon the surface of the upper left quarter A is an ornamentation representing three crosses. The upper right quarter B is ornamented by a band b, extending from the upper left corner of said quarter diagonally across its face and provided with the representation of a column surmounted by a

lamp. The lower right quarter C is ornamented by the representation of a phenix arising from flames. Upon the lower left quarter D is an ornamentation representing a fleur-de-lis. The center of the shield is ornamented by a smaller shield of the same contour as the larger shield. Said smaller shield is ornamented by the representation of a sun issuing from behind clouds.

30 What I claim as new, and desire to secure by Letters Patent, is—

The design for an ornament or badge herein described and shown.

In testimony whereof I sign this specification, in the presence of two witnesses, this 18th day of October, 1897.

35 WILLIAM LESLIE FRENCH.
